UNITED STATES PATENT OFFICE.

WILLIAM ROSENBLUM AND CARL T. BLUME, OF REVERE, MASSACHUSETTS.

COMBINED SOCKET AND RHEOSTAT FOR RADIO USE.

Application filed August 31, 1922. Serial No. 585,533.

To all whom it may concern:

Be it known that we, WILLIAM ROSENBLUM and CARL T. BLUME, citizens of the United States, and residents of Revere, county of Suffolk, State of Massachusetts, have invented an Improvement in Combined Sockets and Rheostats for Radio Use, of which the following description, in connection with the accompanying drawing, is 10 a specification, like characters on the drawing representing like parts.

This invention has for its object to provide a combined socket and rheostat made as a single unit and adapted for use with 15 radio apparatus of the type which uses vacuum valves. In radio apparatus of this type it is customary to provide a socket to receive the vacuum tube, which may function either as a detector tube or as an amplifying tube, and it is also customary to employ a rheostat in connection with the tube and by which the resistance of the tube-filament circuit can be varied.

Heretofore it has been the common practice to make the socket and the rheostat as 25 separate units, in which case it is necessary to wire up each unit separately in making the installation.

One object of our invention is to provide 30 a combined socket and rheostat made as a single unit and which are properly wired in the manufacture so that the rheostat element is permanently connected electrically with the socket element. By using 35 this combined unit the installation of the apparatus is simplified because there is only a single unit to wire up.

Another feature of our invention relates 40 to a novel construction for the combined socket and rheostat by which the socket element is vertically disposed so that the bulb therein will stand upright as usual in radio apparatus while the rheostat is arranged about a horizontal axis. This arrangement 45 has the advantage that when it is installed the control for the rheostat will be situated in a most convenient position to manipulate, while at the same time the bulb or tube will have the vertical arrangement 50 desirable.

Another advantage incident to our invention is that the rheostat control and the vacuum tube always have a fixed relation 55 to each other with the control closely adjacent to the socket and, therefore, in using

the apparatus there will be no chance of mistaking the proper control for any bulb.

Other features of our invention will be more fully hereinafter described and then pointed out in the appended claim. 60

In the drawings, wherein we have illustrated a selected embodiment of our invention,

Fig. 1 is a perspective view of a combined 65 socket and rheostat embodying the invention.

Fig. 2 is an under side view.

Fig. 3 is a section on the line 3—3, Fig. 2.

The device herein illustrated comprises a base member 1 having associated therewith 70 a vertically-disposed socket element 2 adapted to receive a vacuum bulb, said socket element being shown as having a bayonet joint slot 3 to receive a pin extending from the base of the bulb as usual in apparatus 75 of this type.

Situated beneath the base 1 is a plate 4 of insulating material which forms the bottom of the socket 2 and this plate is provided with four apertures 5 to receive the 80 four terminals with which the radio bulbs are usually provided.

Situated beneath the plate 4 are four contacts 6, 7, 8 and 9, which are in the form 85 of resilient strips with which the bulb terminals contact when the bulb is inserted into the socket. The contacts 7, 8 and 9 are connected to the binding posts 10, 11 and 12 respectively, the construction being such that these three contacts are insulated 90 from the base 1. The contacts 9 and 8 are those which correspond to the grid and plate contacts of the bulb and the contacts 6 and 7 are those which correspond to the filament contacts of the bulb. 95

The rheostat is of the usual form comprising a core of insulating material around which is wound a coil of resistance wire and also comprising a contact arm engaging the coil and turnable about an axis to vary the 100 length of the resistance wire which is in the circuit. The core of the rheostat element is shown at 13 and it has an arcuate shape. The resistance wire which is coiled about the core is indicated at 14 and one 105 end of the wire is connected to a binding post 15 to which the circuit wire is attached.

The contact arm of the rheostat is indicated at 16 and it is mounted in a shaft 17 110

which carries a thumb piece or handle 18 by which the shaft may be turned. Said contact arm is electrically connected to the socket terminal 6 so that the circuit through the filament will be from the terminal 15, through the resistance wire 14 to the contact arm 16, thence to the socket terminal 6, through the bulb and to the base terminal 10.

By turning the shaft 17 and adjusting the contact 16 along the coil 14 the amount of resistance wire which is in the circuit can be varied thus varying the resistance of the circuit. In the present invention this rheostat is carried by the base and forms with the socket element a unit construction. The base is formed with the vertical wall 19 which is provided with a bearing 20 in which the shaft 17 is journalled and the wall 19 is shown as having two wings 21 to which the ends of the arcuate core 13 are secured. The shaft for operating the contact arm is thus situated horizontally while the socket is vertically disposed.

Any permanent electrical connection between the contact arm 16 of the rheostat and the socket terminal 6 may be employed without departing from the invention. If the base 1 is made of insulating material then the contact and terminal will be connected by a suitable conductor which forms a permanent part of the unit and does not need to be disconnected from either element when the installation is made. On the other hand if the base 1 is made of metal or a good conductor of electricity then the necessary electrical connection between the contact arm 16 and the socket terminal may be through the metal base. Where this construction is employed it will be sufficient to ground the socket terminal 6 on the base by means of a screw 22 as shown in Fig. 3, be-

cause the arm 16 is electrically connected to the base through the shaft 17.

One advantage of the above arrangement is that the unit may be placed on the bottom of the casing for the radio apparatus and secured thereto with the shaft 17 extending through the front panel 23 of said casing so that the thumb piece or knob 18 will be on the outside of the front panel in position to be operated. By mounting the socket element and the rheostat on the same base and combining them into a single unit the installation of the device in radio apparatus is very much simplified because it involves simply securing the combined unit to the panel or base and then connecting the proper wires to the terminals 10, 11, 12 and 15.

Moreover the socket and the rheostat of the unit always have a fixed position relative to each other wherever they are mounted on a panel or base and, therefore, the control which belongs to any bulb of the apparatus can be accurately determined.

We claim.

A combined socket and rheostat for radio apparatus comprising a base having a vertical flange at one end, a vertically-disposed socket element carried by the base and provided with socket terminals, an arcuate resistance coil carried by said vertical flange, a horizontal shaft journalled in and having electrical connection with said flange and a contact arm fast to said shaft and engaging said resistance coil, one of the socket terminals being grounded on the base.

In testimony whereof, we have signed our names to this specification.

WILLIAM ROSENBLOOM.
CARL T. BLUME.
